UNITED STATES PATENT OFFICE.

JOHN E. WOODBURY, OF WORCESTER, MASSACHUSETTS.

METHOD OF PRINTING.

1,209,098.

Specification of Letters Patent. Patented Dec. 19, 1916.

Original application filed June 4, 1913, Serial No. 771,668. Divided and this application filed July 12, 1915.
Serial No. 39,274.

To all whom it may concern:

Be it known that I, JOHN E. WOODBURY, a citizen of the United States, residing at Worcester, in the county of Worcester and 5 State of Massachusetts, have invented a new and useful Method of Printing, of which the following is a specification.

This is a division of my application for a patent on an apparatus for printing, filed 10 June 4, 1913, Serial No. 771,668.

This invention relates to a method of printing designs and illustrations from intaglio plates. Considerable difficulty has been encountered in doing commercial 15 printing from intaglio plates involving illustrations, because the tinted or half tone parts of the design will not print clearly under ordinary conditions. This is of particular importance in cases involving both 20 illustrations and reading matter which is the usual condition presented in this class of printing. Although the invention relates broadly to this art as specified above, regardless of the particular applications 25 thereof, it is especially applicable to the printing of high class letter-heads and advertisements of various kinds in which it is desired to secure the highest degree of 30 perfection in the printing of illustrative designs of more or less complicated nature. It is well understood that for the purpose 35 of printing such designs, the paper should be moistened, but this has always presented difficulties for the reason that it is difficult to handle moistened sheets at a high enough 40 rate of speed and with sufficient accuracy to do this class of printing within a reasonable cost and yet keep the quality of the highest degree. I have discovered that it 45 is possible to secure the highest class of results by the local moistening of the sheet within the space occupied by the illustration.

This invention, therefore, relates to this 45 method of printing and to the additional steps which I have used for the purpose of carrying out this method in a practicable manner.

Reference is to be had to the accompanying drawings, in which—

Figure 1 is a side view of a well known kind of plate press showing the application of this invention thereto; Fig. 2 is a front elevation of the same; Fig. 3 is a transverse 55 sectional view on the line 3—3 of Fig. 2 on

enlarged scale, and Fig. 4 is a plan of a letter-head printed in accordance with this invention.

The invention is shown as carried out in a printing press of well known type having a frame 10. This frame is provided with the usual power shaft 12 and rotary members 13, the connections between which will not be described herein or shown in full as they are well understood in this art. 60 Connected with these rotary members is an arm or lever 14 connected with a link 15 and operating a slide 16 in a well known way to move it forward and back in guides on the frame. The intaglio plate 17 is held 65 in position below an opening in the feed table 18 which has a slight vertical motion. The paper to be printed upon is registered by the registering devices 19 on the feed table in the usual way. Then a plunger 70 70 ascends, moving the plate up through the feed table against the counter 21. These parts also are well understood, and any desired mechanism can be employed for this purpose, this invention being independent 75 of any particular style of press.

Mounted over an outwardly extending portion 24 of the base of the frame is a platform 25 preferably on about the same level as the feed table when moved up. On this 80 platform are registering devices 26 corresponding with the registering devices 19 for receiving the sheets before they are put into the press proper. The side registers on the platform are shown on the left and those 85 for the press on the right.

Connected with the arm 14 is a flexible connection 30. This is shown as passed around pulleys 31 and connected by a metal connection 32 with the end of the belt 33. 90 This belt is made of a strip of textile material which is capable of taking up moisture and having that moisture spread throughout a given portion thereof so as to be uniformly damped. At the other end this 95 flexible belt is connected by a clamp 34 or the like through another connection 32 with a flexible member 35 which passes over pulleys 36 and is connected with an arm 37 secured on the same shaft as the arm 14 and 100 oscillatable therewith. A slide 38 is connected with the belt and slides along a stationary frame 39 to guide the belt and keep it from flapping. In this way the movement of the arm 14 in one direction is accom- 105 110

panied by the movement of the arm 37, and the two together work the two ends of the combined flexible member, so that the oscillation of these arms causes this belt 33 to move back and forth.

The path of the belt is shown more fully in Fig. 3. It passes under a roller 40 and over a roller 41 which is adjustable by a screw 42. These rollers are mounted on an extension of the platform 25. It then passes adjacent to the registers 26 and under the position which the sheet occupies when registered therein. It then passes over a roller 43 down to the lower clamp 34. On the platform 25 is a block 44 which is provided with a projection 45. This projection extends up into contact with this flexible belt and is of the same size and shape as the illustrative portion of the design of the intaglio plate used on the press and of the counter. It is also located in the same position with respect to the registers 26 that this design on the plate is to the registers 19.

An arm 47 is eccentrically connected with one of the rotary members 13 and pivoted to a lever 48 to which is connected a pivoted platen 49 directly over the block 44. This also is shown as provided with a projection 50 and as being covered with a textile water absorbing sheet 51. This projection registers with the projection 45. These parts obviously work with the press and for each revolution of the press the platen moves down once substantially in contact with the block 44.

Over the belt 33 on the platform 25 is located a stationary sheet 52 which is made of textile material capable of absorbing and holding moisture. This is stretched out between a plate 53 and a clamping member 54 and is shown as of two thicknesses. It is directly upon this that the paper sheet A is located.

In a convenient position is arranged a water pipe 56 having a nozzle 57 with an adjustable valve 58 arranged over the path of the movable belt 33 and not far from the rolls 40 and 41. This valve can be adjusted to any desired flow of water. The belt shifter 60 which controls the starting and stopping of the press in the usual way is provided with an extending end 61 which engages and operates the stem 62 of a controlling valve 63 which permits the operator when shifting the belt to turn on or off the water in the pipe.

When the water is turned on it will drip constantly on the belt in accordance with the adjustment of the valve 58. The water dropping on the belt obviously would spread to some extent by itself but would not spread uniformly under all conditions, and would leave the belt with the most moisture at the center. For the purpose of thoroughly spreading the moisture, the belt is passed

over the rolls 40 and 41. This squeezes the moisture from the center to the edges and keeps the moisture uniform across the belt.

Another important feature in connection with the moistening of the paper consists in the application of a spot of moisture to the double sheet 52 and the application of that moisture with pressure to the sheet of paper. Then as the platen ascends the removal of the pressure permits the absorbent material of the sheet 52 and belt 33 to take up any excess of moisture from the paper, thus preventing the paper being made too wet. Thus the spot is moistened uniformly, and all the sheets are moistened the same degree. It will be understood readily that the excessive wetting of a small spot on a sheet of paper would tend to swell the paper very badly at the moistened spot, and thus make it difficult to handle and difficult to impress it with the design properly without wrinkling or smutting. The primary object of the sheet 52 is to provide a stationary support for the paper.

The paper having been moistened and the moisture having been absorbed, to leave the moisture in a proper condition thereon, the sheet is transferred from the registers 26 to the registers 19. This can be done obviously automatically or by hand, but in the present case the invention is shown as applied to a handpress, and it is intended that the operator shall take the sheets one at a time from the moisture registers and apply them to the printing registers. This is done at the time when the platen 49 is moving up and when the pressure members of the press are separated. At the same time the printed sheet is being removed. The motion of both hands of the operator in taking the sheet from the moisture applying mechanism and putting it into the press and taking the other sheet from the press and piling it up at the side is in the same direction and at the same time. Consequently it does not materially add to the skill or rapidity required of the operator.

In Fig. 4 the sheet A is shown with an illustrative design B and the dotted line C indicates the extent of the application of moisture. It will be seen that the printed matter is not included in the part which is moistened unless it is necessary to provide the printing in the design itself.

In this way it will be seen that a uniform, but not excessive, moisture is applied to each sheet localized over that portion thereof which is to receive the imprint involving the illustrative, that is the tinted or half tone, portion or portions, and the printing is done immediately after the moisture is applied and the excess removed. The perfectly black parts of the design, if they can be separated from the remainder, and the reading matter, do not need this treatment.

Although I have illustrated and described

only one way of carrying out the invention I am aware of the fact that many modifications can be made therein without departing from the scope of the invention as expressed 5 in the claims. Therefore I do not wish to be limited in these respects but

What I do claim is:—

1. A method of printing from intaglio plates which consists in moistening a portion of a sheet, keeping the remainder of the sheet dry, making the impression from the illustrated portion of the intaglio plate on the moistened portion of the sheet and printing on the unmoistened portion of the sheet.
- 10 2. A method of printing from intaglio plates which consists in locally moistening a portion of a sheet, preventing the spreading of the moisture beyond the moistened spot, removing any excess of moisture therefrom, 15 and immediately thereafter printing the illustrative portions of a design from an intaglio plate on the moistened portion of the sheet and the reading matter on the dry portion.
- 20

3. A method of printing from intaglio 25 plates which consists in applying moisture to a sheet on the portions thereof which are to receive the imprint of the illustrative portions of the plate, keeping the rest of the sheet dry including the part to 30 receive the imprint of the reading matter, taking up the excess moisture from the moistened portion, and applying the sheet to the plate from which the imprint is to be made.

4. The method of printing from intaglio 35 plates, which consists in locally moistening a sheet on which the imprint is to be made, then taking up the excess moisture from the moistened portion of the sheet, and printing thereon while the sheet is in that condition. 40

5. The method of printing from intaglio 45 plates which consists in moistening a sheet on certain portions only and printing illustrative matter only on the moistened portions from the intaglio plates.

In testimony whereof I have hereunto set my hand.

JOHN E. WOODBURY.
